UNITED STATES PATENT OFFICE

158,244

LATCH UNIT FOR MOVING PICTURE SCREENS

Hugo Bernzott, Niles, and John T. Heck, Elmhurst, Ill., assignors to Da-Lite Screen Company, Inc., a corporation of Illinois

Application November 4, 1948, Serial No. 149,453

Term of patent 14 years

(Cl. D61—1)

To all whom it may concern:

Be it known that we, Hugo Bernzott and John T. Heck, citizens of the United States, residing at Niles, in the county of Cook, and Elmhurst, in the county of Du Page and State of Illinois, respectively, have invented a new, original, and ornamental Design for a Latch Unit for Moving Picture Screens, of which the following is a specification, reference being had to the accompanying drawing, forming part thereof.

Figure 1 is a perspective view of a latch unit for moving picture screens, showing the two parts separated.

Fig. 2 is a perspective view of the handle member, the lower end of the handle being broken away.

Figs. 3, 4, 5, 6 and 7 are front, side, rear, top and bottom views respectively of the latch unit for moving picture screens.

We claim:

The ornamental design for a latch unit for moving picture screens, as shown.

HUGO BERNZOTT.
JOHN T. HECK.
